TRIMMING MACHINE

Donald G. McLean, Beverly, Mass., and George A. Miner, Goffstown, N. H., assignors to United Shoe Machinery Corporation, Flemington, N. J., a corporation of New Jersey

Application October 22, 1940, Serial No. 362,258

20 Claims. (Cl. 12—88)

This invention relates to machines for trimming such objects as the edges of shoe-soles, it being especially adapted for rough-rounding an outsole about the heel-seat and forming upon the upper margin an inclined surface or rand.

In machines of the character indicated above, the rounding and randing are commonly effected by a high-speed cutter, which throws off chips at a great velocity. These, with any collecting system now in use, tend to fly about the machine, sometimes being of such size and projected with such force as to injure the operator. An object of the invention is to prevent this scattering of the chips and to direct them along predetermined paths. This object is achieved by associating with a rotatable cutter having spaced arms, a hood extending about the cutter and open at one side thereof, and a disk or shield secured at the outer side of the cutter and provided with a series of openings adapted to create a current of air inwardly between the cutter-arms to the interior of the hood. By this current, the chips are carried away from the open side of the hood and delivered within it to the suction set up by the customary factory-system. To increase the strength of the air-current, the disk-openings may be inclined inwardly and rearwardly, and when there is at the outer side of the cutter a rotatable disk, which may be a crease-gage, an ample inflow of air is assured by having in the disk a series of openings. That the direction in which the chips leave the cutter for their passage through the hood may be made more certain, and regardless of the creation of an air-current, there are projections lying between the cutter-arms and having deflecting surfaces inclined inwardly and rearwardly. These projections are preferably upon a disk secured to the cutter-shaft against the outer side of the cutter, so the relation of the deflecting surfaces is unaffected by the grinding of the cutter. This disk may be that in which the air-current-creating openings are formed.

A further object of the invention is to provide for the correct positioning of the work with respect to the cutter, in a manner convenient for the operator and without interference with the effective collection of the chips. To this end, there is movable on the hood previously mentioned, at its open side, a carrier, which may be in the form of an arm, pivoted upon the hood and having rotatable upon it the crease-gage or disk by which the work is located with respect to the cutter, and which also guards the shoe-upper against contact with said cutter. By re-

leasably securing the arm or carrier upon the hood, it may be swung back to give access to the cutter and its attached disk. The chip-collecting hood surrounds the periphery of the cutter at the rear of the machine, while at the front a member for engagement with the tread-surface of a sole extends about the cutter. This tread-engaging member serves both as a cutter-guard and an element of the collecting system, and co-operates with the crease-gage in correctly presenting the work to the cutter. It is preferably mounted to yield upon the hood longitudinally of the cutter-axis, so the work is urged toward the crease-gage and against the randing blade of the cutter, and its position is variable in the same direction so it may better act in connection with soles of different thicknesses. The crease-entering member or gage and the tread-engaging member or guard are carried by a movable mounting common to both, in the present instance the hood. By this, they may be adjusted together longitudinally of the cutter-axis. Consequently, if necessary, they may be quickly located when the cutter is changed, this adjustment not altering their relation to each other as arranged for operation upon soles of a particular thickness.

The accompanying drawings illustrate one of the several embodiments which the invention may assume,

Fig. 1 being a front elevation of our improved machine;

Fig. 2, an enlarged broken front elevation of the elements more closely co-operating with the work;

Fig. 3, an enlarged side elevation of the machine, looking from the left in Fig. 1; and

Fig. 4, a perspective view of the cutter and its shield somewhat separated from each other.

Upon a column 10 the machine-head 12 is mounted, and in this is journaled in ball-bearings 14, 14 a horizontal shaft 16 rotated by power applied through belt-gearing 18. Clamped upon the end of the shaft opposite the driving means is a cutter C, which is shown as having two arms 20, 20 extending oppositely from a tapered hub 22. At the outer extremity of each arm is a transversely extended blade 24, having projecting from its outer end a short inclined blade 26. For the purposes of the present invention, the blades 24, 24 are especially intended for rounding the periphery of an outsole at the heel-seat, while the blades 26, 26 bevel or rand the upper margin of said outsole. The cutter-hub is

forced against a shoulder 28 upon the shaft 16 by a screw 30 threaded into the outer end of said shaft, with its head bearing against a disk or shield 32 surrounding the shaft and forced by the screw against the cutter. The outer face of the shield is shown as beveled toward the periphery to a guard-flange 34 (Fig. 4), which overhangs the randing blades 26. The shield has novel characteristics which will be described later.

To receive the chips produced by the cutter, it has at its opposite sides, above and at the rear, a collecting hood 36, which is preferably joined at 38 to the factory exhaust-system. The hood is shown as supported by an extension 40 secured to the top of the head 12 by slot-and-screw connections 42. These connections permit the adjustment of the hood, and the work-engaging elements which it carries with respect to the cutter longitudinally of its axis. The movement may be facilitated by a screw 44 threaded into the end of the extension 40, and held against longitudinal movement by engagement with the machine-head. The heavier chips, which tend to descend from the cutter, are received by a tray 46 attached to the column by a bracket 48 and connected to the exhaust at 50.

To complete the hood, there is at the front of the cutter C a guard 52, extending about the right side of the cutter, as viewed from the operating position, through about 180°, bearing at its upper edge against a vertical plate 53, which closes an opening at the upper front portion of the hood. The guard is attached by a screw 54 to the end of a horizontal spindle 56, movable in a sleeve 58 which is clamped at 60 in a divided portion of the hood and having a finger-piece 61 by which it, with the guard, may be shifted longitudinally of the cutter-shaft. The guard is urged along the shaft toward its outer end by an expansion-spring 62, situated within the sleeve and interposed between the end of the spindle and a screw 64 threaded into the sleeve, and by which the force exerted by the spring may be altered. The movement of the spindle under the influence of the spring is to an extent permitted by a projection 66 from the spindle, lying in a slot 68 extending longitudinally of the sleeve. As the guard shifts, it moves along the outside of a complementally curved projection 70 from the hood, so that at no time is there a space opened for the escape of chips. In addition to aiding in the collection of chips, the member 52 prevents accidental contact with the cutter C and also furnishes, by a convex surface 72 at its outer side, a rest for the tread-surface of a sole, serving, with an element still to be described, to position the work for operation upon it.

Pivoted at 74 (Fig. 3) upon a bracket 75 at the outer side of the hood 36 is an arm 76, carrying at its inner side a ball-bearing 78 (Fig. 2). The outer raceway of this bearing carries the hub 80 of a disk 82 axially aligned with the cutter C. The periphery of the disk is curved outwardly at 84 over the periphery of the shield 32 and the randing blades 26, which it encircles. The reduced edge 86 is adapted to enter the crease of a shoe being operated upon, guiding this as it is turned by the operator and acting as a gage to determine the depth of the cut made by the blades 24 and 26. The surface 84 of the disk further protects the shoe-upper from the cutter, and, since it turns freely as the work is advanced, it does not rub over and mar said upper

by its contact. In the operating position of the disk 82, the arm may be locked by a removable pin 90, extending through registering vertical openings in the arm and bracket. Upon removal of the pin, the arm and disk may be swung outwardly to give access to the cutter and its shield.

To prevent chips from being thrown laterally from the hood, where the exhaust through the connections 38 and 50 is not fully effective, the disk or shield 32 has means for creating an inward air-current past the cutter. This consists of a circular series of openings 92, which lie at an angle to the cutter-axis, being inclined inwardly and rearwardly with respect to the direction of rotation, as indicated by the arrow in Fig. 4. As the rear sides of these openings strike the air in their revolution, they draw this in and force it between the cutter-arms 20 back into the hood. That air may be supplied freely for this blower-effect, it is admitted to the openings 92 through a circular series of openings 94 in the gage-disk 82. To prevent the chips from being caught in the depressions 96 at the front of the revolving arms 20 and building out to the blades 24, where they would be cut repeatedly, the inner side of the shield 32 is provided with two projections 98, 98 which are so formed that they will occupy considerable portions of the depressions. The forward side of each projection is inclined at 100 inwardly and rearwardly, and, striking the chips, deflects them away from the arms in the same direction as is taken by the air-currents through the openings 92. The inclined projections upon the shield are furnished instead of correspondingly beveling the cutter-arms, because it frees these surfaces from the effect produced by grinding back the cutter. This would weaken the arms, and the blades may become so reduced that shoulders would be formed in the arms generally parallel to the axis of rotation. These shoulders would interfere with the chips, as they roll back from the cutter-blades, and in them said chips would tend to gather. It is customary to provide for use with cutters of this character a plurality of shields of different diameters, so, as said cutter is reduced by grinding, the relation between its periphery and that of the shield may be kept reasonably constant. This change of shields, with their differently arranged projections, maintains the arm-depressions 96 substantially occupied by the deflecting surfaces and free from chip-retaining depressions.

Using the apparatus with the work held in the hands of the operator, the margin of an out-sole O, attached to an upper U and projecting about the heel-seat, is presented to the cutter C (Fig. 2). This presentation is best effected by forcing the tread-surface of the sole inwardly and to the right against the curved surface 72 of the rest 52, pressing this back slightly against its spring 62 and then allowing the spring to carry the work oppositely into operating position. In this movement, the crease between the sole and the upper seats itself upon the gage-disk 82, this engagement determining the depth to which the cutter will operate. The force exerted by the expanding spring constantly urges the upper margin of the sole toward the gage-disk 82, steadyng the work and holding it against displacement as the operator turns it to present the periphery of the heel-seat-portion to the cutter. When there is a substantial change in the thickness of the sole, the operator may vary the space between the tread-rest 52 and

the crease-gage 82 by altering the longitudinal location of the sleeve 58 through the clamp 60. When a new cutter is substituted, its overall length may change. This may be compensated for by shifting the hood 36 upon the head 42 by its slot-and-screw connections 42. In so doing, any adjustment, which may have been made for sole-thicknesses by the positioning of the rest 52 will be unaffected, because this rest and the crease-gage 82 are moved together by the common mounting furnished by the hood. With the cutter almost entirely surrounded by the hood 36 and the rest 52, and a current of air flowing strongly in through the gage-disk-openings 94, the shield-openings 92 and over the deflecting surfaces 100 of the shield, the chips are conducted with certainty back into the collecting system, being neither thrown toward the operator nor about the machine, while the cutter itself is guarded by the shield-projections 98 from gathering chips.

Having described our invention, what we claim as new and desire to secure by Letters Patent of the United States is:

1. In a trimming machine, a rotatable cutter having spaced arms, a hood extending about the cutter and open at one side thereof, and a disk secured to the cutter at the outer side, said disk being provided with a series of openings adapted to create a current of air inwardly between the cutter-arms to the interior of the hood.

2. In a trimming machine, a rotatable cutter having spaced arms, a hood extending about the cutter and open at one side thereof, and a disk secured to the cutter at the outer side, said disk being provided with a series of openings each inclined inwardly from the outer side to the spaces between the cutter-arms and rearwardly with respect to the direction of rotation of the cutter.

3. In a trimming machine, a rotatable cutter having spaced arms, a hood extending about the cutter and open at one side thereof, a disk secured to the cutter at the outer side, said disk being provided with a series of openings adapted to create a current of air inwardly between the cutter-arms to the interior of the hood, and a disk mounted to turn at the outer side of the cutter and having a series of openings through which air is delivered to the cutter-disk-openings.

4. In a trimming machine, a rotatable cutter having spaced arms, a hood extending about the cutter and open at one side thereof, and a disk secured to the cutter at the outer side, said disk being provided with projections lying between the cutter-arms and having surfaces inclined inwardly and rearwardly with respect to the direction of rotation of the cutter and arranged to deflect the chips from the cutter into the hood.

5. In a trimming machine, a rotatable cutter having spaced arms, a hood extending about the cutter and open at one side thereof, and a disk secured to the cutter at the outer side, said disk being provided with a series of openings adapted to create a current of air inwardly between the cutter-arms to the interior of the hood, there being surfaces situated between said cutter-arms by which chips under the influence of the air-current are deflected rearwardly with respect to the direction of rotation of the cutter.

6. In a trimming machine, a rotatable shaft, a cutter fast upon the shaft at one extremity and having spaced arms, a disk secured upon the shaft against the cutter at its outer side and

provided with chip-deflecting projections extending between the cutter-arms, and a hood about the cutter to receive the deflected chips.

7. In a trimming machine, a rotatable shaft, a cutter fast upon the shaft at one extremity and having spaced arms, a disk secured upon the shaft against the cutter at its outer side and provided with chip-deflecting projections extending between the cutter-arms, there being openings through the disk between the projections, and a hood about the cutter to receive the deflected chips.

8. In a trimming machine, a rotatable shaft, a cutter fast upon the shaft at one extremity and having spaced arms, a disk secured upon the shaft against the cutter at its outer side and provided with chip-deflecting projections extending between the cutter-arms, a hood about the cutter to receive the deflected chips, and a disk freely rotatable upon the hood outside the cutter-disk.

9. In a trimming machine, a rotatable shaft, a cutter fast upon the shaft at one extremity and having spaced arms, a disk secured upon the shaft against the cutter at its outer side and provided with chip-deflecting projections extending between the cutter-arms, there being openings through the disk between the projections, a hood about the cutter to receive the deflected chips, and a disk freely rotatable upon the hood outside the cutter-disk and provided with openings.

10. In a trimming machine, a rotatable cutter, a chip-collecting hood extending about the cutter and open at one side thereof, a carrier movable upon the hood at the open side and provided with a bearing, and a crease-gage rotatable upon the bearing adjacent to the cutter and in axial alignment therewith.

11. In a trimming machine, a rotatable cutter, a chip-collecting hood extending about the cutter and open at one side thereof, an arm pivoted upon the hood outside the opening thereof, a gage-disk rotatable upon the arm, and means for releasably securing the arm with the gage-disk adjacent to the cutter.

12. In a sole-trimming machine, a rotatable cutter, a chip-collecting hood surrounding the periphery of the cutter at the rear of the machine, and a member having a convex tread-engaging surface extending peripherally about the cutter at the front of the machine.

13. In a sole-trimming machine, a rotatable cutter, a chip-collecting hood surrounding the periphery of the cutter at the rear of the machine, and a tread-engaging member extending about the cutter at the front of the machine and mounted to yield upon the hood longitudinally of the cutter-axis.

14. In a sole-trimming machine, a rotatable cutter, a chip-collecting hood surrounding the periphery of the cutter at the rear of the machine, a tread-engaging member extending about the cutter at the front of the machine, and means arranged to vary the normal position of the engaging member longitudinally of the cutter-axis.

15. In a sole-trimming machine, a rotatable cutter, a chip-collecting hood extending about the cutter and provided with a tubular portion, a spindle mounted upon the tubular portion for limited longitudinal movement along the axis of the cutter, a tread-engaging member fixed upon the spindle, and a spring situated in the tubular

portion and urging the tread-engaging member to a normal position outside the cutter.

16. In a sole-trimming machine, a rotatable cutter, a crease-entering member situated at one side of the cutter, a tread-engaging member spaced from the crease-entering member, and a movable mounting common to the two members and by which they may be adjusted together longitudinally of the cutter-axis.

17. In a sole-trimming machine, a rotatable cutter, a crease-entering member situated at one side of the cutter, a tread-engaging member spaced from the crease-entering member, a movable mounting common to the two members and by which they may be adjusted together longitudinally of the cutter-axis, and means arranged to vary the space between the members.

18. In a sole-trimming machine, a rotatable cutter, a chip-collecting hood extending about the cutter, a crease-entering disk rotatable upon the hood, a cutter-guard mounted upon the hood and adapted for engagement with the tread-surface of the sole, and means arranged to position

the hood differently longitudinally of the axis of the cutter.

19. In a sole-trimming machine, a rotatable cutter, a chip-collecting hood extending about the cutter, a crease-entering disk rotatable upon the hood, a cutter-guard mounted upon the hood and adapted for engagement with the tread-surface of the sole, means arranged to position the cutter-guard upon the hood at different normal distances from the crease-disk, and means arranged to position the hood differently longitudinally of the axis of the cutter.

20. In a sole-trimming machine, a rotatable cutter, a chip-collecting hood extending about the cutter, a crease-entering disk rotatable upon the hood, a cutter-guard mounted upon the hood to yield from the crease-gage and adapted for engagement with the tread-surface of the sole, and means arranged to position the hood differently longitudinally of the axis of the cutter.
